Application July 11, 1950, Serial No. 173,090

5 Claims. (Cl. 118—263)

1

This invention pertains to material applying rolls, more especially to an improved roll for applying gum to the surface of the label-picking element of a labeling machine.

In my copending application for Letters Patent, Serial No. 167,181, filed June 9, 1950, now Patent No. 2,609,305, I have disclosed a labeling machine wherein the gum is applied to a picker by a roller whose axis is always in the same plane (at least during the gum-applying operation) while the surface of the picker to which the gum is applied may, at times, lie in either of two spaced adjacent planes parallel to the plane of the roll axis. In order that the periphery of the roll may contact the picker when the latter is in either of its gum-receiving positions it is requisite that the roll be of such construction or so supported that its effective radius at the point of contact with the picker may vary, at least, by the spacing of the two planes which the picker may occupy while receiving gum. In my aforesaid application I have described a gum-applying roll which is of soft rubber and so designed as to be capable of very substantial variations in contact radius. Such a roll is effective for the intended purpose so long as the labels which are to be applied are not of excessive width, but if large labels are to be applied, necessitating the use of a very long gum-transfer roll, the force necessary to compress such a rubber roll (as that disclosed in the aforesaid application) to its smallest working radius, results in a contact pressure which is excessive for optimum spreading of the gum.

The present invention has for its principal object the provision of the material-applying roll so devised that its effective contact radius, while it is applying the material, is variable to a substantial amount without requiring excessive contact pressure. A further object is to provide a gum-applying roll for use in a labeling machine in which the axis of the gum-applying roll is always in the same plane while the surface of the picker to which the gum is applied may, at times, lie in either of two spaced adjacent planes parallel to the plane of the roll axis. A further object is to provide a material-applying roll having a cylindrical applying element of substantially unchanging diameter but so supported that the radial distance between its axis of rotation and the picker contacting element of the roll may vary to a substantial extent. A further object is to provide a gum-applying roll, for use in labeling machines, having a cylindrical gum-applying roll of hard, substantially unyielding

2

material, the roll having a rigid supporting shaft but with provision for permitting the roll to move bodily radially of the shaft in opposition to resilient means tending to keep the roll centered on the shaft. Other and further objects and advantages of the invention will be pointed out in the following more detailed description and by reference to the accompanying drawings wherein

Fig. 1 is a longitudinal, diametrical section through a roll embodying the invention;

Fig. 2 is an end elevation of the roll;

Fig. 3 is a side elevation of a resilient element used in the construction of the roll;

Fig. 4 is an end elevation of the resilient element of Fig. 3; and

Figs. 5 and 6 are diagrammatic views showing two different relations of the roll and the picker of a labeling machine.

Referring to the drawings, and particularly to Figs. 5 and 6, the letter P designates the picker of a labeling machine, shown as having the horizontal upper surface S to which the gum is applied. At times, during the operation of the labeling machine, the picker occupies the position shown in Fig. 5 wherein its gum-receiving surface S is in the horizontal plane indicated by the line W—Z, while at other times in the operation of the machine surface S, when receiving gum, lies in a different horizontal plane designated by the line X—Y. When in either of these positions the picker receives gum from a gum-transfer roll mounted on a shaft whose axis, at least during the gum-applying operation, always lies in the same horizontal plane, this plane being

designated in Fig. 5 by the line C—D and in Fig. 6 by the line A—B, it being understood that the lines A—B and C—D indicate the same horizontal plane. While the axis of the shaft which carries the gum-transfer roll always lies in this

same horizontal plane (designated by the lines A—B and C—D) the cylindrical gum-applying roll 10 itself (in order that it may contact the surface S of the picker in either of the positions shown in Figs. 5 and 6) is arranged for bodily movement relative to the axis of its supporting shaft 11 so that it becomes eccentric to said shaft when applying gum to the picker surface. While it is possible that in one of the positions, for example the position shown in Fig. 6, the gum-applying element of the roll may be concentric with the axis of the shaft, it is preferred, in accordance with the present invention, that it be eccentric to the axis of the shaft in both positions of the picker, in order to insure a proper spreading pressure.

55

This roll 10, in accordance with the present invention, is illustrated more fully in Figs. 1 to 4 inclusive. As shown, this roll 10 is of an axial length several times its diameter, as is requisite when, in apparatus of the type to which the invention pertains, it is required to apply gum to very large labels. The shaft 11 of this roll is rigid and intended to be held stationary, that is non-rotatably, in suitable supporting means (not shown) forming a part of the labeling machine structure. For example, the opposite ends of the shaft may be held fixed in suitably shaped sockets in a horizontally moving transfer carriage. On the shaft 11 there is mounted a sleeve 12, preferably of an internal diameter somewhat greater than the internal diameter of the shaft and having at each end an inserted bearing bushing 13, for example of bronze, nylon, powdered metal, or other suitable bearing material, the sleeve 12 turning freely on the shaft 11.

Surrounding the sleeve is a cylindrical shell 14 which may be of steel or other suitable material, but which is substantially rigid, that is to say it does not yield radially or become deformed in response to the pressures to which it is subjected during the gumming operation. This shell is preferably provided with inwardly directed radial flanges 15 and 16 at its opposite ends and is normally coaxial with the shaft 11. Within the chamber 17, between the outer surface of the sleeve 12 and the inner surface of the shell 14, there is arranged yieldable supporting means for the shell such that the latter may be considered to float on the sleeve 12 with permissive bodily movement in a radial direction relatively to the shaft so that the shell may, at times, become eccentric with reference to the axis of the shaft 11. As here illustrated, this yieldable supporting means consists of a series of coiled springs 18 (Figs. 3 and 4). While a single spring might be employed (extending throughout the length of the roll) it is preferred to use a plurality of shorter springs assembled together, since such shorter springs are easier to manufacture; are useful in making up rolls of different lengths; and in assembled relation providing greater uniformity of support throughout the length of the shell. As illustrated, each spring 18 comprises end coils 19 and 20 of relatively large diameter, and intermediate coils 21, at least one of which, 21^a, is of an internal diameter such as snugly to embrace the sleeve 12, the coils 19 and 20 being of a diameter to fit snugly within the shell 14. In assembling the parts the necessary number of springs is threaded over the sleeve 12 and disposed within the chamber 17, the large end coils of adjacent springs abutting each other and the outer end-most coils of the series engaging the inner surfaces of the flanges 15 and 16. The arrangement is such that the springs are under some axial compression when so installed, thus holding the parts in proper assembled relation so that each of the springs bears with substantially the same pressure against the inner surface of the shell 14. The ends of the chamber 17 are preferably closed by washers 23 held in place by pins 24 passing through the shaft 11. While the outer surface of the metal shell 14 may, itself, constitute the gum-applying element, it is preferred to provide a jacket 22 of non-metallic material embracing the shell 14 and which actually applies the gum to the picker. This jacket 22 may be of any suitable material having such a degree of resiliency as may be

desired for the particular purpose. However, it has been found that vulcanized rubber of a durometer hardness of 35 gives excellent results when employed for this purpose, it being desirable that the gum-applying peripheral surface of the roll be sufficiently unyielding so that it will apply the gum with uniform pressure throughout the entire length of the roll.

While one desirable embodiment of the invention has herein been illustrated by way of example, it is to be understood that the invention is broadly inclusive of any and all modifications falling within the scope of the appended claims.

I claim:

1. In combination with a labeling machine picker having a surface designed to receive a coating of gum while said surface lies in either of one or the other, respectively, of two parallel planes, a roll for applying gum to said picker surface and a shaft on which the roll is mounted, the axis of the roll-shaft lying in a single predetermined plane, which is spaced from but parallel to the gum-receiving surface of the picker whether the gum-receiving surface of the picker occupies one or the other of said gum-receiving positions, the roll being of an axial length at least as great as the width of the picker surface to which the gum is applied, characterized in that the gum-applying roll comprises a substantially rigid cylindrical shell whose outer peripheral surface constitutes the gum-applying element, and resilient means normally centering the shell relatively to the axis of the roll-shaft, said resilient centering means being so constructed and arranged as to permit the shell to contact the gum-receiving surface of the picker while the axis of the roll-shaft lies in said predetermined plane and when the picker occupies either one or the other of said gum-receiving positions, respectively.
2. In combination with a labeling machine picker having a surface which receives a coating of gum while said surface lies in either of one or the other, respectively, of two parallel planes, a roll for applying gum to said picker surface and a shaft on which the roll is mounted, the axis of the roll-shaft lying in a single predetermined plane, which is spaced from but parallel to the gum-receiving surface of the picker whether the gum-receiving surface of the picker occupies one or the other of said gum-receiving positions, the roll being of an axial length at least as great as the width of the picker surface to which the gum is applied, characterized in that the roll comprises a unitary, substantially rigid shell encased in a layer of resilient, non-metallic material having a durometer hardness of the order of 35 and whose outer peripheral surface constitutes the gum-applying element, the roll being arranged to turn freely on its shaft, and roll-centering means comprising at least one open-coiled spring coaxial with the roll-shaft, said roll-centering means normally supporting the shell in coaxial relation to the shaft, the roll-centering means being so designed that said shell-encasing layer of the roll may contact the gum-receiving surface of the picker when the axis of the roll lies in said predetermined plane and whether the picker occupies either one or the other of its gum-receiving positions.
3. In combination with a labeling machine picker having a surface which receives a coating of gum while said surface lies in either of one

or the other, respectively, of two parallel planes, a roll for applying gum to said picker surface and a shaft on which the roll is mounted, the axis of the roll-shaft lying in a single predetermined plane, which is spaced from but parallel to the gum-receiving surface of the picker whether the gum-receiving surface of the picker occupies one or the other of said gum-receiving positions, the roll being of an axial length at least as great as the width of the picker surface to which the gum is applied, characterized in that the gum-applying roll comprises a cylindrical sleeve having a bearing bushing at each end, the bushings turning freely on the roll-shaft, a unitary, rigid, cylindrical shell of a length at least as great as that of the sleeve and of a greater internal diameter than the diameter of the sleeve, said shell having an inwardly directed, integral, radial flange at each end, a plurality of open-coiled springs all coaxial with the sleeve, each spring comprising a coil which snugly embraces the sleeve and coils which bear against the inner surface of the shell, the springs being held under axial compression by said radial flanges and normally holding the shell in coaxial relation to the shaft, and a layer of vulcanized rubber of a durometer hardness of the order of 35 encasing the shell and having a smooth, peripheral surface which constitutes the gum-applying element, the springs being so designed that the rubber layer which encases the shell may contact the picker while the axis of the roll-shaft lies in said predetermined plane and when the picker occupies either one or the other of said gum-receiving positions, respectively.

4. In combination with a labeling machine picker having a surface which receives a coating of gum while said surface lies in either of one or the other, respectively, of two parallel planes, a roll for applying gum to said picker surface and a shaft on which the roll is mounted, the axis of the roll-shaft lying in a single predetermined plane, which is spaced from but parallel to the gum-receiving surface of the picker whether the gum-receiving surface of the picker occupies one or the other of said gum-receiving positions, the roll being of an axial length at least as great as the width of the picker surface to which the gum is applied, characterized in that the roll comprises a sleeve which turns freely on the roll shaft and a unitary, rigid, cylindrical shell encased in a layer of non-metallic material whose peripheral surface forms the gum-applying face of the roll, the sleeve having radial, inwardly directed flanges at its opposite ends, respectively, coil springs, each comprising relatively large end coils and relatively small intermediate coils, arranged within the shell with the smaller coils snugly embracing the sleeve and

with the larger coils contacting the inner surface of the shell whereby the shell is normally held in coaxial relation to the shaft, the springs being held under axial compression by the radial flanges at the ends of the sleeve whereby the several springs exert substantially equal radial pressure against the inner surface of the shell, the springs being so designed that the shell-encasing layer may contact the picker while the axis of the roll shaft lies in said predetermined plane and while the picker occupies either of said gum-receiving positions.

5. In combination with a labeling machine picker having a flat gum-receiving surface which at times is disposed for the reception of gum in either one or another of two parallel planes, a gum transfer roll for applying gum to said picker surface and which has a shaft whose axis always lies in a single predetermined plane, parallel to 15 but spaced from the gum-receiving surface of the picker when the roll is applying gum to the picker, the roll comprising a sleeve coaxial with said shaft, a rigid cylindrical shell of an internal diameter greater than the external diameter of the 20 sleeve and which has a peripheral gum-applying surface and radial inwardly-directed integral flanges at its opposite ends respectively, and a plurality of coiled springs arranged in end-to-end coaxial relation within the shell, each spring 25 comprising a large coil at each end and a smaller intermediate coil, the smaller coils snugly embracing the sleeve and the larger coils contacting the inner surface of the shell, the several springs 30 being under axial compression, with a large coil 35 of each endmost spring engaging the respective radial flange of the shell, the springs normally holding the shell in coaxial relation to the roll-shaft, but being so designed that while the axis of the roll-shaft lies in said predetermined plane, 40 the peripheral surface of the roll may operatively contact the gum-receiving surface of the picker when the picker occupies either one or the other of its gum-receiving positions.
